UNITED STATES PATENT OFFICE.

WILLIAM N. FURTHMANN, OF CHICAGO, ILLINOIS, ASSIGNOR TO THOMAS H. TAPLEY,
OF GRAND RAPIDS, MICHIGAN.

FURNACE.

1,135,678.

Specification of Letters Patent. Patented Apr. 13, 1915.

Application filed July 30, 1913. Serial No. 782,009.

To all whom it may concern:

Be it known that I, WILLIAM N. FURTHMANN, citizen of the United States, residing at Chicago, in the county of Cook and State of Illinois, have invented a certain new and useful Improvement in Furnaces, of which the following is a full, clear, concise, and exact description.

My invention relates to improvements in heating appliances.

The objects of my invention are to provide a device of this character of increased efficiency; to provide an improved arrangement for insuring continued circulation of the air to be heated through the heating chambers; to provide improved means for insuring a continuous supply of fresh air to the heating chambers; to provide means for supplying heated air to the combustion chamber; and to provide a device which is simple, durable and which requires little attention.

I have illustrated, in the accompanying drawings, the preferred embodiment of the invention. It is to be understood, however, that said invention may be embodied in other forms.

In the drawings, Figure 1 is a sectional elevation of the preferred structure; Fig. 2 is an enlarged, top, plan view of the adjustable drip pan; Fig. 3 is a bottom plan view of the combined deflector and cover; Fig. 4 is an enlarged bottom plan view of the burner cap; Fig. 5 is an enlarged top plan view of the burner with the cap removed; Fig. 6 is an enlarged, sectional elevation of the feed tube; Fig. 7 is an enlarged, top plan view of the overflow cup; and Fig. 8 is a perspective view of a support.

The device comprises a burner 1 of suitable construction, hereinafter described more fully, said burner being located at the base of a combustion chamber 2, the latter being supported on suitable standards or legs 3. The heated products of combustion pass upwardly through the chamber and out through a suitable pipe or outlet 4. Within the chamber 2 an inner chamber 5 is located, the latter being spaced from the former and supported on suitable standards or brackets 6, whereby a free space is provided around all sides of said inner chamber, the latter being thereby subjected to the above mentioned heated gases as they pass upwardly from the burner. Fresh air is admitted to

the inner chamber 5 through a suitable pipe 7. The apparatus as illustrated is shown mounted in an inclosure 8, as, for example, a room of a house, the chamber 5 having open communication therewith, whereby the heated air from said chamber 5 passes directly into said inclosure 8 and circulates in the manner indicated by the arrows. However, it is to be understood that the device may be used as a furnace and located in the basement of a building in the usual manner, under which circumstances the heating chamber 5 would communicate with the usual pipes leading to the upper floors. In the arrangement shown, wherein it is intended to maintain a certain predetermined temperature within a given inclosure, the inlet pipe 7 extends preferably through the wall of said inclosure whereby fresh air is drawn in from the outside. The products of combustion also pass out of said inclosure through the pipe 4.

The burner 1, previously referred to, is preferably an oil burner, liquid fuel being supplied through the pipe 9 and the flow thereof controlled by a suitable valve having a housing 10 and a plunger 11 in the form of a needle valve, the latter having a small opening therein (see dotted lines in Fig. 1) whereby there is a continuous, although limited, flow of oil through the valve even when the plunger is seated. Said plunger is carried on a pivoted lever 12, movement being imparted to the latter by a suitable thermostatic expansion device 13 having thin flexible walls, the detailed construction of which device is well known. The movement of the lever is limited by a suitable adjusting device 14 which limits the upper movement of the left hand end of said lever as shown in Fig. 1. The thermostatic device controls the valve in such a manner as to vary the fuel supply and thereby maintain a definite predetermined temperature in a manner which will be more fully described herein-after.

The oil or other fluid, after passing the valve just described, accumulates in a receptacle 15 having glass walls 16 whereby the level of the fluid may be observed. A pipe 17 leads from said receptacle and connects with a suitable coupling 18 (see Fig. 6). Said coupling has a tube 19, the latter having a plurality of radial openings 20 at its upper end

22
but being closed at the top. An inner adjustable tube 21 is also carried by said bushing 18 and is provided at its lower end with a funnel shaped extension 22 provided with a suitable screen 23 preferably of gauze, through which the air is screened which passes upwardly through the inner tube to the burner. The oil which enters through the pipe 17 fills the tube 19 and flowing out through the openings 20, partially fills the cone-shaped recess in the burner 1. The level of the liquid fuel in said recess is the same as that in the receptacle 15. Said fuel, upon being ignited, furnishes the necessary heat to heat the air or other medium in the inner chamber 5. It will be seen that the area of the liquid varies with the level thereof because of the cone-shaped recess or receptacle. Accordingly the flame may be adjusted by adjusting said level by the operation of the inlet valve.

10 The burner 1 includes a suitable frame or spider 24, the latter carrying also a cylindrical element 25 having a cap 26 with an enlarged central opening. The construction will be readily understood from Fig. 1 and is such that air is supplied to the burner adjacent to the liquid fuel through the opening in the burner cap 26 and also through the tube 21. A further supply of air is admitted around the cylindrical element 25. If the fuel level in the burner becomes so high that the oil overflows, said oil is caught and restrained by a circular flange 27 at the 15 base of the burner 1. If the oil overflows said flange, it is caught within a shallow pan 28 adjustably supported on the screw threaded tube 19. Said pan, by being adjusted up or down, acts as a damper to vary the air supplied to the burner and also acts as a shade to prevent the light from being thrown downwardly, a feature that is of considerable importance in certain classes of service.

20 15 The pan 28 is provided with a plurality of holes 29 through which the accumulated oil may drain into a cup-shaped member 30, the latter being also supported on the tube 19 and being provided with a drain pipe 31 through which the overflow oil may be removed.

25 It will be seen that the burner is of such construction that any accumulation of soot will float on the liquid and will not plug up the holes 20 or interfere with the automatic supply of fuel as the level of the liquid is

normally above said holes. To aid in inspecting the burner and also in cleaning the device, the bottom 32 of the inner chamber 5 is made removable in an upwardly direction, being provided with a suitable ring or eyelet 33, whereby a rod with a hook on the end may be lowered through the chamber and said bottom raised thereby, exposing the burner and its associated parts to view and rendering them accessible for cleaning purposes. Said bottom comprises a pair of disks 34, 35 held apart by a pedestal 36. The lower disk acts as a deflector, as shown by the arrows.

30 20 It will be seen that there is no direct communication between the passages through which the burnt products of combustion are drawn and the air within the inclosures 8 which it is desired to heat. Accordingly said air is not contaminated. The fresh air is drawn in through the outer walls of said inclosure and passing directly into the heating chamber 5 near the lower end thereof, it passes upwardly about as indicated by the arrows and by virtue of the central enlargement of said heating chamber, ample heating area is provided to heat said air the desired amount. The heated air passing out through the top of the heating chamber circulates within the inclosure about as shown by the arrows, and part of it is drawn into the burner to supply the necessary oxygen. The air supplied to the burner accordingly is heated air. The air discharged into the inclosure is heated not only from having been within the chamber 5, but also by being brought in direct contact with the walls 2 of the outer inclosure of the heater. Accordingly very little heat is wasted. The thermostatic device 13 responds to the temperature of the heated air and by varying the fuel supply, maintains said air at the desired predetermined temperature.

25 25 What I claim is:

30 In a heating device, a cylindrical chamber open at the top, and having a central enlargement, and a removable bottom comprising a pair of disks spaced apart by a central pedestal, one of said disks acting as a heat deflector.

35 In witness whereof, I, hereunto subscribe my name this 26th day of July, A. D. 1913.

WILLIAM N. FURTHMANN.
